CYLINDER BLOCK FOR TWO-CYCLE ENGINES

Elmer C. Kiekhaefer, Cedarburg, Wis.

Original application August 12, 1953, Serial No. 373,783.
Divided and this application January 13, 1958, Serial
No. 708,520

4 Claims. (Cl. 123—73)

This invention relates to two-cycle internal-combustion engines and particularly to the method of forming the transfer passage and intake ports of the cylinder for effecting the directional control of the fuel mixture into the cylinder and more complete scavenging of the engine.

The invention provides a preformed sleeve cast within a cylinder block with a transfer passage formed therein to extend approximately to the center of the intake ports which are thereafter drilled in the block to form corresponding channels at the end of the transfer passage and which direct the fuel mixture into the cylinder.

An object of the invention is to simplify the manufacture of the cylinder blocks for internal-combustion engines.

Another object is to provide for the more controlled flow of the fuel mixture into the cylinder so that there is obtained a more complete scavenging or clearing of the cylinder of the exhaust gases.

Another object is to provide guide means for the directional control of the fuel mixture through the ports of the cylinder sleeve and support of the sleeve between the ports referred to.

Another object is to increase the volumetric efficiency of the engine and the better flow of the fuel mixture through the transfer passage.

These and other objects and advantages will be more fully set forth in the following description of an embodiment of the invention illustrated in the accompanying drawings.

In the drawings:

Figure 1 is a plan view of the engine with parts of the crankcase and cylinders broken away and sectioned;

Figure 2 is an elevation of the base of one of the cylinders shown in Figure 1 as taken on line 2—2 of Figure 1;

Figure 3 is a section taken on line 3—3 of Figure 2 before the port is formed in the cylinder;

Figure 4 is a view similar to Figure 3 showing the port as formed therein and completed; and

Figure 5 is a section taken on line 5—5 of Figures 2 and 4.

The engine 1, shown in the drawings, includes the crankcase 2 which carries one end of the crankshaft 3 in the bearings 4. The valve unit 5 closes the corresponding opposite end of crankcase 2 and is secured by the air intake member 6 which carries a carburetor, not shown, and provides for the introduction of a fuel mixture from the carburetor to the crankcase chamber 7. The pistons 8 are connected to the opposite throws 9 of crankshaft 3 by the rods 10 for reciprocation in opposed relation.

Each cylinder block 11 is provided with a cast-iron sleeve 12 which is cast within the block and carries the corresponding piston 8 for reciprocation therein. The base flange 13 of each cylinder block 11 is provided with a planiform face 14 which is adapted to be bolted against the corresponding opposite faces of crankcase 2. The inner end of each sleeve 12 projects from flange 13

2

into the crankcase and opens into the crank chamber 7. The outer end of each cylinder block 11 is fitted with a threaded opening to receive the base of the spark plug 15 and is otherwise closed to provide a combustion chamber 16. The series of radially formed fins 17 are cast integrally with each cylinder block 11 and provide for cooling of the cylinder by air passing exteriorly thereof.

In the operation of the engine, the pistons 8 move simultaneously in opposite directions to effect compression of the fuel mixture within the combustion chamber 16 of each cylinder. During such movement, valve unit 5 is open to allow the fuel mixture which includes air at atmospheric pressure to enter the crank chamber 7 through air intake member 6. During the power stroke of each piston 8 effected by the simultaneous combustion of the fuel charges in chambers 16, the pistons move toward each other to compress the fuel mixture within the crankcase chamber 7. Towards the end of the power stroke of the pistons, the ports 18 in cylinder blocks 11 are uncovered by pistons 8 and opened to receive the initial exhaust of the burned gases from the respective combustion chambers 16. Shortly thereafter, the ports 19 of the cylinders are similarly uncovered by pistons 8 to provide for the communication of the respective chambers 16 with crank chamber 7 through the corresponding transfer passages 20. With the opening of ports 19, the compressed fuel mixture within the crank chamber enters chambers 16 of the cylinders and displaces the exhaust gases remaining therein and refills the chambers 16 with a fuel charge.

According to the invention as shown in the drawings, each passage 20 is formed as a recess in each block 11 on each side of sleeve 12. Each recess opens from face 14 of the respective block alongside the sleeve of the block.

Each recess providing a transfer passage 20 is formed by a core, not shown, which extends from the base of the cylinder alongside sleeve 12 and up to the location of ports 19. The inner end face 21 of each recess is formed angularly with respect to the sleeve as shown in Figure 3 to coincide with the centerlines of ports 19.

The cross-section of each passage 20 as formed by the core decreases from the base of cylinder block 11 to ports 19 which facilitates withdrawal of the core. The decreasing cross-section results in an acceleration of the fuel mixture as it travels the length of the passage from crank chamber 7 to ports 19.

The face 21 defining the upper end of the passage is formed by a core to define an acute angle with the outside of sleeve 12. The angle referred to is generally determined by the desired angularity of the stream of fuel mixture to enter the combustion chamber 16 through ports 19 which are formed by drilling after the casting of the cylinder block 11 has been completed and the core forming the passage has been withdrawn.

The ports 19 are formed by drilling at spaced locations on center lines which coincide generally with end face 21 of the recess so that in the process of drilling the ports, the several corresponding channels 22 are formed in the block 11. Each channel is separated by the portions 23 of the block remaining therebetween.

The larger circular recesses 24 are formed in the outer portion of block 11 concentrically of the drilled holes to receive the plugs 25 which are seated in recesses 24 to close the outer holes formed in block 11 in drilling ports 19, as described.

The ports 19 may be accurately located with respect to the end face 21 of transfer passage 20 by tool means, not shown, which may be indexed relative to the face 14 of base flange 13.

Passage 20 is of decreasing cross-section from face 14 of block 11 to the end 21 of the passage and extends immediately adjacent to sleeve 12 so that the fuel mixture which passes over the sleeve directly cools the adjacent portions of the sleeve.

The fuel mixture reaching the end of each passage 20 enters channels 22 and is deflected and directed thereby through the corresponding ports. Liquid particles carried in the fuel mixture and reaching the end of passage 20 are similarly deflected through ports 19 into the cylinder so that no accumulation of liquid fuel is allowed to develop.

The fuel mixture is directed through the ports with a less turbulent flow and in generally straight lines of flow. The construction advocated by the present invention provides that the wall thickness of the portion of the ports on the transfer passage side of end face 21 is limited to the thickness of the sleeve 12 providing a more direct flow of the fuel mixture into the combustion chamber 16.

The precise angular direction, location and size of each port may be selected to attain the desired scavenging and recharging characteristics for the engine cylinder.

This application is a division of abandoned application, Serial No. 373,783, filed August 12, 1953, and entitled, "Cylinder Block for Two-Cycle Engines and Method for Making the Same."

Various modes of carrying out the invention are contemplated as being within the scope of the following claims particularly pointing out and distinctly claiming the subject matter which is regarded as the invention.

I claim:

1. In a cylinder block for a two-cycle internal-combustion engine including a crankshaft carried by a crankcase and a piston connected to the crankshaft for reciprocation; said cylinder block comprising a wear-resistant sleeve having a combustion chamber at one end thereof and adapted to support the piston for reciprocation therein, the other end of said sleeve being open and communicating with the chamber of said crankcase, said block surrounding said sleeve and having an end corresponding to the crankcase end of the sleeve secured to the engine crankcase and provided with at least one recess adjoining said sleeve and communicating with said crankcase chamber, said recess having an inner end face provided with a number of channels in predetermined radial relation to the axis of the said sleeve and of circular section, said block further including a series of corresponding inner and outer holes respectively aligned with the corresponding channels and extending through the block and sleeve, said inner holes forming ports whereby the fuel mixture from the crankcase passing to the end of said recess into said channels is directed by the channels through said ports into said combustion chamber, and means closing said outer holes.

2. The invention of claim 1 wherein the block is provided with a recess on opposite sides of the sleeve and said channels together with the corresponding ports in said sleeve have projected axes which substantially intersect at a location within the sleeve more remote from

the end of the sleeve communicating with the crankcase chamber than said ports.

3. In a cylinder block for a two-cycle internal-combustion engine including a crankshaft carried by a crankcase and a piston connected to the crankshaft for reciprocation; said cylinder block comprising a wear-resistant sleeve having a combustion chamber at one end thereof and adapted to support the piston for reciprocation therein, the other end of said sleeve being open and communicating with the chamber of said crankcase, said block surrounding said sleeve and having a corresponding end secured to the engine crankcase and provided with at least one recess immediately adjoining said sleeve and communicating with said crankcase chamber, said recess having an inner end face including a number of ribs defining channels therebetween and in predetermined angular relation to the axis of the said sleeve, said block further including a series of corresponding inner and outer holes respectively aligned and extending through the block and sleeve, 10 said channels and the inner holes being in accurate alignment, said inner holes forming ports whereby the fuel mixture from the crankcase passing through said recess is directed by the channels into the combustion chamber of the sleeve, the ribs defining said channels extending 15 into said recess to support the portions of the sleeve between the ports thereof.
4. In a two-cycle internal-combustion engine including a crankshaft carried by a crankcase and a piston connected to the crankshaft and employing crankcase induction and precompression of a fuel mixture, a cylinder block confining a wear-resistant cylindrical sleeve having a combustion chamber at one end thereof and communicating with the crankcase chamber at the other end thereof and adapted to support the piston for reciprocation 20 therewithin, said block surrounding said sleeve and having an end corresponding to the crankcase end of the sleeve secured to the crankcase and provided with at least one recess immediately adjacent said sleeve and communicating with said crankcase chamber, said recess having a 25 decreasing cross-section in the direction away from the crankcase to provide for acceleration of fuel mixture passing therethrough to the sleeve combustion chamber and terminating in an end face forming an acute angle relative to the sleeve, said block further including a plurality of 30 spaced circular bores extending through the block and its sleeve to provide a series of inner and outer openings in said block, said bores having their respective axes disposed to coincide generally with the end face of the recess and intersecting said recess to form corresponding 35 arcuate channels in the end face, the inner openings of 40 said bores forming ports whereby the fuel mixture from the crankcase passing through the recess and directed by the channels is admitted to the combustion chamber, and 45 means closing said outer openings.
